(57) **CLAIM**

The ornamental design for an inverter alternating current busbar, as shown and described.

DESCRIPTION

FIG. 1 is a perspective view of a first embodiment of an inverter alternating current busbar;

FIG. 2 is a rear view of the inverter alternating current busbar shown in FIG. 1;

FIG. 3 is a front view of the inverter alternating current busbar shown in FIG. 1;

FIG. 4 is a left side view of the inverter alternating current busbar shown in FIG. 1;

FIG. 5 is a right side view of the inverter alternating current busbar shown in FIG. 1;

FIG. 6 is a top view of the inverter alternating current busbar shown in FIG. 1;

FIG. 7 is a bottom view of the inverter alternating current busbar shown in FIG. 1;

FIG. 8 is a perspective view of a second embodiment of the inverter alternating current busbar;

FIG. 9 is a rear view of the inverter alternating current busbar shown in FIG. 8;

FIG. 10 is a front view of the inverter alternating current busbar shown in FIG. 8;

FIG. 11 is a left side view of the inverter alternating current busbar shown in FIG. 8;

FIG. 12 is a right side view of the inverter alternating current busbar shown in FIG. 8;

FIG. 13 is a top view of the inverter alternating current busbar shown in FIG. 8; and,

FIG. 14 is a bottom view of the inverter alternating current busbar shown in FIG. 8.

The broken lines depict portions of the inverter alternating current busbar which form no part of the claimed design.
